PAGE 2

FIG. 1 is a perspective view of a combined lighting and heating fixture showing my new design as seen from the bottom and one end thereof;

FIG. 2 is a side elevational view of the fixture;

FIG. 3 is an end elevational view of the fixture; and

FIG. 4 is another perspective view of the fixture looking down on the same from a corner thereof.

The dominant features of my design reside in the portion shown in full lines.

I claim:

The ornamental design for a combined lighting and heating fixture, as shown and described.
